US00D658030S

(12) **United States Design Patent**
Stuckey et al.

(10) **Patent No.:** **US D658,030 S**
(b4) **Date of Patent:** **** Apr. 24, 2012**

(54) **DISH**

(75) Inventors: **David Martin Stuckey**, Eaglemont (AU); **Marc Fraser**, Doncaster East (AU)

(73) Assignee: **David Stuckey Investments Pty Ltd** (AU)

(**) Term: **14 Years**

(21) Appl. No.: **29/392,257**

(22) Filed: **May 19, 2011**

(30) **Foreign Application Priority Data**

Nov. 19, 2010 (AU) 15127/2010

(51) **LOC (9) Cl.** **08-06**

(52) **U.S. Cl.** **D8/321**

(58) **Field of Classification Search** ..... D8/331, D8/341, 338, 333, 300–303, 306, 321, 350–353, D8/311–314, 316, DIG. 1; D12/190, 195, D12/404, 405; 292/356, 357, 207, 223, DIG. 31; 70/91, 101, 208, 211; 16/412, 413, 416, 16/445, 402, 11 R, 111 R

See application file for complete search history.
